UNITED STATES PATENT OFFICE.

THOMAS GREGORY McCONNELL, OF COLLINSVILLE, ILLINOIS.

POTATO-PLANTER.

SPECIFICATION forming part of Letters Patent No. 394,596, dated December 18, 1888.

Application filed August 16, 1888. Serial No. 282,860. (No model.)

To all whom it may concern:

Be it known that I, THOMAS GREGORY McCONNELL, a citizen of the United States, residing at Collinsville, in the county of Madison, State of Illinois, have invented new and useful Improvements in Potato-Planters, of which the following is a specification.

My invention relates to improvements in potato-planters; and it consists in certain novel features hereinafter described and claimed.

In the annexed drawings, Figure 1 is a side view of a potato-planter provided with my improvements, the near carrying-wheel being removed. Fig. 2 is a plan view. Fig. 3 is a side view showing the check-row operating mechanism, and Fig. 4 is a front view of the same.

Referring to the drawings by letter, A designates the main frame, consisting of a U-shaped bar provided on its front end with the ears B, in which the tongue C is secured. The axle D is mounted in suitable bearings, E, secured to the lower sides of the main frame, and 25 is provided with carrying-wheels F, one of which is secured rigidly to the end of the axle.

G designates a multiple cam-wheel secured rigidly on the axle adjacent to one of the carrying-wheels, and H designates a lifter pivoted to the side of the main frame in rear of said cam-wheel and projecting over the same, the under edge of said lifter resting on the said cam-wheel and the front end of the lifter 35 being turned downward and then forward and projecting under a pin, I, projecting laterally from the vertical arm of the picker.

J designates a vertical tube secured to the outer side of the main frame in advance of the cam-wheel and forming a bearing for the vertical arm K of the picker L. The outer side of this tube J is provided with a vertical slot, M, having its central portion curved upward and rearward, so as to give the picker a 45 rotary motion as it moves up and down in the said tube. The pin I on the vertical arm K of the picker projects through this slot and normally rests on the front end of the lifter H. The vertical arm K of the picker rests 50 loosely in the tube J, so as to move freely therein, and a horizontal arm, N, extends inward from the upper end of the vertical arm

and is provided in its extremity with a downwardly-projecting pin, O, which is adapted to enter the potatoes, as will be hereinafter more 55 fully referred to.

P designates a comb secured on the upper side of the frame at the front end thereof and projecting rearward over the upper end of the planting-tube Q. This comb consists of a small 60 block or casting having its rear edge provided with a series of teeth, R. The planting-tube is composed of a flexible tube, S, and an open-ended hollow block, T, secured to the upper end of the tube S and affixed to the underside 65 of the comb P, the teeth R of the comb being immediately over the upper end of the said block T.

In the under side of the tongue I form a recess, U, in which is pivoted the upper end of 70 the front vertical arm of an L-shaped lever, V, the longer horizontal arm of said lever projecting rearward and having its end secured to a tubular standard, W, which receives the lower end of the flexible tube S 75 and has a shovel, X, secured to its lower end. On the rear side of this tubular standard, at the lower end of the same, is formed a socket, Y, in which is pivoted the front end of a fork, Z, a covering-roller, a, being journaled 80 in the rear free end of said fork and carried thereby.

b designates small shovel-plows secured to the opposite sides of the tubular standard and projecting rearward and downwardly 85 therefrom. These plows are curved, as shown, so as to engage the earth on the sides of the furrow and throw the same inward over the dropped potatoes.

c designates a compound lever, which is fulcrumed to the inner side of the main frame and has its front end extending downward from its fulcrum and then bent inward and projecting under the L-shaped lever V. The rear portion of this lever c projects downward 95 and rearward under the axle, so as to clear the same, and is then bent upward, as clearly shown, and provided at its extremity with a small rearwardly-turned lip, d.

e designates a gravity latch or pawl, which 100 is pivoted to the side of the main frame and is provided at its upper end with a hook or shoulder, f, which normally engages the lip d of the lever. The rear end of said lever is

thus held depressed and its front end is elevated, and the said front end, bearing against the under side of the lever V, consequently raises the said lever V and holds the tubular standard, the shovels, and the covering-roller off the ground when the machine is not in use as a planter or is being carried from field to field.

The driver's seat *g* is secured on a suitable standard, *h*, projecting upward from a cross-bar, *i*, secured to the main frame adjacent to the latch *e* and in rear of the hopper. The said hopper *j* is secured upon the main frame and is provided with a downwardly and forwardly inclined bottom, *k*, and a trough, *l*, on its front side, forming a continuation of said inclined bottom. An opening, *m*, is formed in the front side of the hopper to allow the potatoes to pass into the said trough.

20 In operation the potatoes are placed in the hopper, as will be readily understood, and the machine is then drawn over the ground. As the machine is drawn along, the carrying-wheels will be revolved and the axles carried

25 along with it, thereby rotating the cam-wheel. As the cam-wheel rotates, the points of the same will bear against the under edge of the lifter and raise the same, giving the front end of the lifter an upward vertical movement, 30 causing it to strike against the pin on the picker, and thereby raise the said picker. When the picker is at its lowest position, its horizontal arm projects over the trough on the front side of the hopper, the pin on the 35 inner end of the picker entering a potato in the trough, so that the potato can be carried to the planting-tube. As the cam-wheel continues its rotation, the lifter will be lowered, so that the picker can drop by its own gravity.

40 As the picker is raised, the slot in the vertical tube, acting on the pin on the picker, causes it to swing toward the planting-tube, carrying the potato thereto. The picker reaches the comb and the pin on its inner end 45 enters the teeth of the comb just before the picker has reached the upper limit of its vertical movement, so that continued vertical movement will draw the pin through the comb and release the potato therefrom. The potato 50 then falls through the planting-tube and the tubular standard to the furrow, and is covered by dirt thrown thereon by the curved shovels and pressed by the covering-roller. Upon the downward movement of the picker the slot in 55 the vertical tube causes the horizontal arm to swing over the trough and then be lowered, causing the pin on the end of said arm to pierce another potato and secure it to be planted. The picker is thus moved between

60 the trough and the planting-tube continuously during the travel of the machine and the potatoes planted at regular intervals, and the said intervals may be made greater or less by providing the cam-wheel with a larger or 65 smaller number of cam-faces, as will be readily understood.

The construction just described will be

found very desirable by reason of its simplicity; but I prefer the mechanism illustrated in Figs. 3 and 4. This mechanism is 70 operated by a check-row wire, and consists of a rock-shaft, *2*, journaled in the upper side of the main frame at the front end thereof and having its ends *3* carried past the carrying-wheels and bent downward, as shown. The 75 extremities of these downwardly-turned ends are shaped to form hooks *n*, through which the check-wire passes. The downwardly-bent ends of the rock-shaft are further provided with lugs *o* adjacent to the hooks *n*, and 80 levers *p* are pivoted on these lugs, the rear ends of said levers being adapted to contact with the hubs of the wheels, and the front ends being provided with an enlargement, *q*, as shown. A coiled spring, *r*, is arranged 85 around this shaft and has its free end bearing on the main frame to hold the shaft in its normal position, and the shaft is further provided with a rearwardly-extending arm, *s*, which projects under the pin *O* of the picker, 90 as shown.

In operation the check-wire is stretched across the field in the usual manner and passed through the hook *n*, as will be readily understood. As the machine is drawn along, 95 the knobs on the check-wire, striking against the hooks, will tend to rotate the rock-shaft, so as to cause the arm *s* to raise the picker, and the levers, striking against the hub of the carrying-wheels, will release the knobs from 100 the hooks when the planting has been accomplished.

It will be understood, of course, that the pivoted lifter is dispensed with when the check-row mechanism is employed.

Having thus described my invention, what I claim, and desire to secure by Letters Patent, is—

1. In a potato-planter, the combination of the main frame, the hopper mounted thereon, 110 the planting-tube carried by the main frame, a vertically-movable vibrating picker adapted to convey the potatoes from the hopper to the planting-tube, and mechanism for raising and vibrating said picker, as set forth.

2. The combination, with the main frame, of the hopper secured thereon, the horizontal comb secured to the main frame in advance of the hopper, the planting-tube depending from said comb, the horizontally-vibrating 120 picker mounted on the side of the main frame and adapted to convey the potatoes from the hopper to the planting-tube and be engaged by the comb, and mechanism for vibrating said picker, as set forth.

3. The combination, with the main frame, of the hopper mounted thereon, the planting-tube mounted on the main frame, the vertical tube secured to the side of the main frame and having a cam-slot in its side, the picker having a vertical arm mounted in said tube, and an inwardly-projecting horizontal arm at the upper end of the vertical arm, the said vertical arm being provided

with a pin projecting laterally through the cam-slot in the vertical tube, whereby when the vertical arm is raised the horizontal arm will be vibrated between the hopper and the 5 planting-tube, and mechanism for raising the vertical arm, as set forth.

4. The combination, with the main frame, of the hopper mounted thereon and having an inclined bottom and provided on its front 10 side with a trough forming a continuation of said bottom, the comb secured to the main frame, the planting-tube depending from the comb, and the picker mounted on the side of the main frame and having a vibrating horizontal 15 arm provided with a pin adapted to engage the potatoes in the trough and be engaged by the teeth of the comb, and mechanism for operating the picker, whereby it will be caused to convey the potatoes from 20 the trough to the planting-tube, as set forth.

5. The combination of the main frame, the hopper mounted thereon, the planting-tube carried by the main frame, the vertical tube secured to the side of the main frame and 25 having a cam-slot in its side, the picker mounted in said tube and having a lateral pin projecting through the cam-slot therein, and provided at its upper end with an inwardly-extending horizontal arm, the rock- 30 shaft journaled on the main frame and having an arm bearing against the under side of the pin on the picker, and mechanism for operating said shaft, whereby the picker will be raised and vibrated between the hopper and 35 the planting-tube, as set forth.

6. The combination of the main frame, the tongue secured thereto and having a recess in its under side, the lever pivoted at its front end in said recess and extending rear-

ward therefrom, the tubular standard secured to the rear end of said lever, the shovels secured to the opposite sides of said standard, the lifting-lever pivoted to one side of the main frame and having its front end bent laterally and projecting under the 40 lever pivoted to the tongue, and the latch pivoted at the rear end of the main frame and engaging the rear end of the lifting-lever, as set forth. 45

7. The combination, with the main frame, 50 of the hopper mounted thereon, the planting-tube carried by the main frame, the vertical tube secured to the main frame and having a cam-slot in its outer side, the picker mounted in said tube and having a pin projecting through the slot therein, and the 55 rock-shaft journaled on the main frame and adapted to engage said pin, as set forth.

8. The combination, with the main frame, of the hopper mounted thereon, the planting-tube carried thereby, the picker mounted 60 on the frame and adapted to convey the potatoes from the hopper to the planting-tube, the rock-shaft journaled on the main frame and adapted to operate the picker and having 65 its ends bent downward and provided with hooks, and the levers pivoted to said ends and having their rear end bearing against the hubs of the carrying-wheels and their front ends enlarged and extending in front 70 of the said hooks, as set forth.

In testimony that I claim the foregoing as my own I have hereto affixed my signature in presence of two witnesses.

THOMAS GREGORY McCONNELL.
